UNITED STATES PATENT OFFICE.

PETRO TRARARA, OF BENTON HARBOR, MICHIGAN.

DESIGN FOR A CHILD'S BARBER CHAIR.

Application filed June 25, 1925. Serial No. 13,890. Term of patent 7 years.

To all whom it may concern:

Be it known that I, PETRO TRARARA, a subject of the King of Italy, residing at Benton Harbor, in the county of Berrien and State of Michigan, have invented a new, original, and ornamental Design for Child's Barber Chairs, of which the following is a specification, reference being had to the accompanying drawing, forming a part thereof.

I claim.

The ornamental design for a child's barber chair, as shown.

PETRO TRARARA.
